UNITED STATES PATENT OFFICE

146,056

DESIGN FOR A GARMENT HANGER

Leon Levin, New York, N. Y.

Application December 22, 1945, Serial No. 124,987

Term of patent 7 years

(Cl. D80—8)

To all whom it may concern:

Be it known that I, Leon Levin, a citizen of the United States, residing at New York, in the county of New York and State of New York, have invented a new, original, and ornamental Design for a Garment Hanger, of which the following is a specification, reference being had to the accompanying drawing, forming part thereof.

In the drawing:

Fig. 1 is a perspective view of a garment hanger, showing my new design; and Fig. 2 is a top view thereof.

I claim:

The ornamental design for a garment hanger, substantially as shown.

LEON LEVIN.
